GRAIN SPOUT HOLDER

Filed Oct. 12, 1928

UNITED STATES PATENT OFFICE

WILLIAM KUTZ, OF RAVENNA, NEBRASKA

GRAIN-SPOUT HOLDER

Application filed October 12, 1928. Serial No. 312,189.

This invention relates to a grain spout holder particularly adapted for maintaining a grain spout in proper position while transferring grain from elevators or warehouses into box cars, but it is to be understood that the holder may be used in connection with a grain spout anywhere the latter is used to effect the transfer of grain from one place to another.

10. The primary object of the invention is to provide, in a manner as hereinafter set forth, a device which may be secured in any desired position without the necessity of anyone constantly tending the spout and which may be 15 adjusted from time to time to change the position of the spout in either a longitudinal or lateral direction with respect to the receptacle into which the grain is being transferred.

With the foregoing and other objects in 20 view the invention consists in the novel construction, combination and arrangement of parts as hereinafter more particularly described and illustrated in the accompanying drawings, wherein for the purpose of illustration is shown an embodiment of my invention, but it is to be understood that changes, 25 variations and modifications may be resorted to which fall within the scope of the invention as claimed.

30. In the accompanying drawings in which like numerals are employed to designate like parts throughout the same:

Figure 1 is a side elevation of an embodiment of my invention showing the same in 35 operative position with respect to a grain spout and a granary door.

Figure 2 is a top plan view of the embodiment of my invention shown in Figure 1.

Figure 3 is a section taken on the line 3—3 40 of Figure 2.

Figure 4 is a section taken on the line 4—4 of Figure 2.

Figure 5 is a fragmentary end elevation of the embodiment illustrated in Figure 1.

45. Referring in detail to the drawing the numeral 1 designates a grain receptacle which may be a bin, box car, or the like, and the numeral 2 designates the door ledge for said receptacle. Secured to the ledge 2 is a clamping device 3 which is substantially in the form

of a U-shaped strap having its end members disposed on opposite sides of the ledge 2. One end of the strap 3 is provided on its inner face with a plurality of spikes 4 which are adapted to engage the side of the ledge when an inward pressure, relative to the ledge, is exerted on the spikes. The opposite end of the strap 3 is provided with a bore 5 having a threaded wall for engagement with the externally threaded end 6 of a crank 7. 55 As the threaded end 6 is rotated by means of the crank 7, the innermost extremity 8 of the threaded end 6 is forced against the side of the ledge 2, opposite the spikes 4, and the spikes 4 are thereby drawn into biting contact with the ledge 2. 60

Swivelly mounted on the upper face of the strap 3 is a vertically disposed yoke 9, within the bifurcated upper end of which a tube 10 is pivoted to swing on a horizontal axis. Extending through the tube 10 is a rod 11 which is provided with a plurality of spaced, transversely extending openings 12 for successive alignment with a pair of openings 13 extending transversely through the tube 10 adjacent 75 one end of the latter.

The rod 11 is formed at one end with a reduced neck 14, whereby the rod 11 is provided with a shoulder 15. The reduced end 14 is adapted to be inserted through an apertured lug 16 which is formed on and depends from a split hoop 17. When the rod 11 and split hoop 17 are in assembled relation, the shoulder 15 provided on the rod 11 abuts against the inner face of the apertured lug 16 whereby the extent of movement of the rod 11 through the lug 16 is limited. One end of the split hoop 17 terminates in a laterally extending, apertured ear 18 and the other end of the split hoop 17 is in the form 85 of a threaded stem 19 which is adapted to be passed through the apertured ear 18 and secured in position by means of a suitable nut 20. By manipulation of the nut 20, the diameter of the split hoop 17 may be 90 varied as desired. The split hoop 17 is adapted to engage a spout as indicated at 21, the mouth of which may be moved towards or away from the door ledge 2 by the adjustment of the rod 11 with respect to the 95 100

5 tube 10. The openings 13 through the tube 10 may be brought into alignment with any of the openings 12 through the rod 11 desired and the rod 11 held against movement relative to the tube 10 by the insertion of a pin 22 through the aligned openings.

10 Secured to the door ledge 2, in spaced relation of the strap 3 is a strap 23 which is preferably formed in the same manner as the strap 3 and has associated therewith a crank 24. Extending through the top of the strap 23 is a stud 25 over which is fitted an eye 26, formed on one end of a guide rod 27. The guide 27 is formed at its opposite 15 end with an eye 28 through which the rod 11 extends. A washer 29 fits over the stud 25 and is forced into frictional contact with the eye 26 by means of a suitable nut 30 threaded on the outer end of the stud 25 in order to prevent the guide rod 27 from pivoting around the stud 25.

20 It will be apparent that the swivel mounting of the yoke 9 with respect to the clamping devices and the pivotal mounting of the tube 10 with respect to the yoke 9 provides a 25 universal joint connection between the tube and the clamping device. By loosening the nut 30, the grip end 31 of the rod 11 may be moved in a lateral direction, by means of 30 which the mouth of the spout 21 may be positioned at any angle desired with respect to the yoke 9. After the mouth of the spout 21 has been moved into the position desired, 35 any further movement may be prevented by means of the pin 22 and the nut 30.

40 It is to be understood that the form of the invention herewith shown and described is to be taken as the preferred example of the same, and that various changes in the details of construction may be resorted to without departing from the spirit of the invention of the invention or the scope of the appended claims.

45 What I claim is:

1. A grain spout holder comprising, a rod, 50 a tube through which said rod extends, said tube having its wall provided with a pair of aligned openings, said rod being formed with a plurality of spaced openings extending transversely therethrough for selective 55 registration with the openings through said tube for the reception of a pin therethrough, means for connecting one end of the rod to a grain spout, means including a universal joint connection for mounting said tube with respect to a grain receptacle, and means for locking 60 said universal joint connection against movement.

65 2. A grain spout holder comprising, a rod, 65 a tubular supporting member therefor adjustable longitudinally of the rod, a vertically disposed yoke having said supporting member pivoted within the bifurcated end thereof to swing on a horizontal axis, a clamp 70 for swivelly mounting said yoke with respect

70 to a grain receptacle, means for connecting one end of the rod to a grain spout, and means whereby any swivel movement of said yoke may be prevented.

75 In testimony whereof, I affix my signature hereto.

WILLIAM KUTZ.
